UNITED STATES PATENT OFFICE.

WILLIAM STEPHEN RAWLINGS, OF MARSHALL, INDIANA.

CAN OR JAR LIFTER.

1,255,791.

Specification of Letters Patent. Patented Feb. 5, 1918.

Application filed September 10, 1917. Serial No. 190,567.

To all whom it may concern:

Be it known that I, WILLIAM S. RAWLINGS, a citizen of the United States, residing at Marshall, in the county of Parke and State 5 of Indiana, have invented certain new and useful Improvements in Can or Jar Lifters; and I do declare the following to be a full, clear, and exact description of the invention, such as will enable others skilled in the art 10 to which it appertains to make and use the same.

This invention relates to new and useful improvements in can or jar lifters.

The primary object of the invention is to 15 provide a device which is especially designed for removing fruit cans or jars from a receptacle containing boiling water in which they are immersed while the contents of the jars are being cooked, the device being so 20 constructed that it can be readily and easily engaged with the can or jar while the same is in the water, and be disengaged therefrom and placed in an upright position upon the 25 table or other support without requiring the user touching the can or jar with his hands.

A further object of the invention is to provide a device of this character which will be extremely simple, strong, durable and 30 inexpensive in construction, efficient and reliable in operation, and well adapted to the purpose for which it is designed.

With these and other objects in view, the invention consists of certain novel features 35 of construction, and the combination and arrangement of parts as will be hereinafter fully described and claimed.

In the accompanying drawings:

Figure 1 is a side elevation of a jar and 40 a device constructed in accordance with this invention, showing the latter in the act of being engaged with the jar;

Fig. 2 is a similar view showing the device engaged with the jar;

Fig. 3 is a sectional view taken on the plane indicated by the line 3—3 of Fig. 2; and,

Fig. 4 is a perspective view of the device.

Referring more particularly to the drawings the numeral 1 designates a handle, which is preferably made of wood or some other suitable material which is substantially a non-conductor of heat. The handle 1 is provided with a longitudinally extending bore for receiving the shank portions of 55 the can or jar engaging members 3 and 4.

The jar engaging member 3 is formed from a single length of comparatively strong wire by bending it intermediate of its ends into two substantially parallel portions 5 and 6. These portions 5 and 6 are bent laterally and inwardly at their lower ends as at 7 and connected by a cross bar 8 which is curved longitudinally as shown. The upper ends of the portions 5 and 6 are bent laterally inwardly as at 9 to form a pair of arms, and the free ends of the arms 9 are struck upwardly to form shanks 10 which are extended through the bore 2 of the handle 1 and upset at their upper ends over the top 70 of the handle to provide a means for securing the jar engaging member 3 to the latter.

The other jar engaging member 4 is constructed of comparatively thick resilient wire in a manner similar to the manner in 75 which the member 3 is constructed with the exception that it is not provided at its lower end with the inturned portions 7, but the lower ends of the parallel portions 11 of this member 4 are connected by a longitudinally 80 curved cross bar 12. The upper ends of the portions 11 are bent laterally inwardly to form arms 13, the inner ends of which are struck upwardly to form shanks 14 which are extended through the bore of the handle 85 and upset at their upper ends. The member 4 is of considerably less length than the member 3 and is spaced away from the same for a purpose which will be now described.

It is to be noted that the inturned lower 90 ends 7 of the portions 5 and 6 of the member 3 and the cross bar 8 forms what may be termed a step.

In using the device, assuming that the jars to be moved are immersed in an upright position in a receptacle containing 95 boiling water, the device is first held in an inclined position with its shorter jar engaging member 4 disposed downwardly, and the top of the jar between the ends of the two 100 jar engaging members. The device is then moved downwardly and at the same time moved into a vertical position, the members 3 and 4 being thus engaged with the opposite sides of the jar. When the step carried 105 at the lower end of the member 3 passes below the lower end or bottom of the jar, it will spring under the same, owing to the fact that the member 4 is resilient and tends to hold the member 3 in tight contact with 110 the jar. The device with the jar inserted between the members 3 and 5 can then be

raised out of the receptacle and carried to the table or other support whereon the jar is to be placed. The jar is rested in an upright position upon the support and the 5 lifter is moved to an inclined position with the shorter member 4 disposed downwardly and at the same time raised. This causes the stop carried by the member 3 to be removed from beneath the bottom of the jar 10 and allows the entire device to be disengaged from the same without requiring the user to touch the jar with his hands.

From the foregoing description taken in connection with the accompanying drawings, the construction, use and operation of 15 the device will be readily understood without a more extended explanation.

As various changes in form, proportion and in the minor details of construction may 20 be resorted to without departing from the spirit of this invention, it is to be understood that I do not wish to be limited to the construction herein shown and described other than as claimed.

25 I claim:

1. A jar lifter of the class described comprising a single handle, a pair of substantially parallel resilient jar engaging members rigidly attached to said handle and extending longitudinally from the same, one 30 of said members being shorter than the other and having a jar receiving seat at its free end, and an inwardly extending step at the free end of the other or longer member, said 35 step being adapted to engage beneath the bottom of a jar when the device is in use.

2. A jar lifter of the class described comprising a pair of parallel members adapted 40 to engage opposite sides of a jar throughout a considerable portion of the length of said sides, one of said members being resilient 45 to permit it to spring away from the other member while the device is being placed upon a jar and one of said members being shorter than the other member, an inwardly 50 extending step at the lower end of the longer member, said step being adapted to engage beneath the bottom of the jar, and a handle to which said members are rigidly connected.

55 3. A device of the class described comprising a pair of substantially parallel jar

engaging members, one of said members being formed from a single length of wire bent intermediate of its ends to form two parallel portions having their lower ends connected by a longitudinally curved cross bar and their upper ends bent inwardly to form arms, a handle to which the inner ends of 60 said arms and the other member are connected, said other member being longer than the first named member and having an inwardly extending step formed at its lower end.

4. A device of the class described comprising a handle, a pair of jar engaging members connected at their upper ends to said handle, one of said members being longer than the other and being formed from a single length of wire bent intermediate 65 of its ends to form a pair of parallel portions, the upper ends of which are bent inwardly and attached to said handle, the lower ends of said portions being bent inwardly and being united by a longitudinally 70 curved cross bar to form a step at the lower end of this member.

5. A device of the class described comprising a handle having a bore extending longitudinally therethrough, a pair of substantially parallel jar engaging members, each of which is formed from a single length 80 of wire being bent intermediate of its ends to form a pair of parallel portions, the upper ends of said portions being bent inwardly to form arms, the latter having their inner ends struck upwardly to form shanks which are extended through the bore of said handle to attach said members to the latter, the parallel portions of one of said members 85 being united by a longitudinally curved cross bar, the parallel portions of the other member being longer than those of the first member and having their lower ends bent inwardly and united by a longitudinally 90 curved cross bar to form a step.

In testimony whereof I have hereunto set my hand in the presence of two subscribing witnesses.

WILLIAM STEPHEN RAWLINGS
